UNITED STATES PATENT OFFICE

WILLIAM F. ROTERMUND, OF SEATTLE, WASHINGTON.

QUICK-ADJUSTING WRENCH.

1,373,529.

Specification of Letters Patent.

Patented Apr. 5, 1921.

Application filed March 30, 1920. Serial No. 369,998.

To all whom it may concern:

Be it known that I, WILLIAM FREDERICK ROTERMUND, a citizen of the United States of America, and resident of the city of Seattle, in the county of King and State of Washington, have invented certain new and useful Improvements in Quick-Adjusting Wrenches, of which the following is a specification.

- 10 My invention relates to wrenches and particularly to wrenches of the type in which one jaw is movable and is provided with means whereby it may be quickly released to shift it by a sliding movement.
- 15 The object of my invention is to provide a wrench in which the movable jaw may be quickly released and locked in place relative to the other jaw and to provide a wrench having these characteristics which is of a 20 simple construction and cheap to manufacture.

The particular features of which my invention consists will first be described in the specification and then particularly pointed 25 out in the claims.

The drawings show wrenches which embody the features of my invention and in the construction which is now most preferred by me.

- 30 Figures 1 and 2 are respectively side and back edge views of a wrench of one construction.

Fig. 3 is a side view of a wrench embodying the same principles of construction, but 35 differing slightly in its construction.

Fig. 4 is a transverse section taken on the line 4-4 of Fig. 1.

The wrench as shown in Figs. 1 and 2 has an outer jaw 1 which extends laterally from 40 a shank 2. As shown in the drawings the fixed jaw 1 is formed integral with the shank 2. This is a feature which, while desirable, is however not strictly essential.

The movable jaw 3 has a sleeve or base 45 section 30 which is adapted to encircle the shank 2 and to slide freely thereon. As illustrated, this jaw and its sleeve are cut from a single piece of sheet metal which is bent so as to encircle the shank and shaped 50 to form a snug sliding fit thereon, excepting in this respect, that at the back of the shank it extends to such a distance as to form a chamber adapted to receive the locking bolt 4. This chamber, at the back of the shank, 55 is also threaded and the back edge of the shank similarly threaded forming a rack 20.

The locking bolt 4 is threaded to conform to the threading in the sliding jaw and upon the edge of the same so that when the bolt is in place it forms a snug and yet freely 60 turnable fit in the sleeve, and when placed so as to also engage with the rack 20 forms a secure lock to prevent movement of the sliding jaw along the shank.

To permit free sliding movement of the 65 inner jaw when desired the bolt 4 is provided with a flattening surface 40 at one side, of such extent that when the bolt is turned so as to present this face to the edge of the shank it will become entirely disengaged 70 from said shank and prevent free sliding of the jaw. To enable the bolt 4 being readily turned when desired, its inner end is provided with a laterally extending arm 41 or with any other type of construction which 75 will enable this bolt to be engaged and turned by the fingers. By turning the arm 41 down so that it extends outward in lateral direction, the jaw may be freed to move it in or out and then by turning the handle 80 41 upward so as to extend in the general plane of the wrench, the inner jaw is securely locked in position.

The wrench shown in Fig. 3 includes the 85 same principle of construction. In the case of the wrench shown in Figs. 1 and 2, the handle is formed by an extension of the shank. In the wrench shown in Fig. 3 the handle 5 extends laterally from the shank and would more correctly be said to form 90 an extension of the outer or fixed jaw 1. In other respects the wrenches are essentially alike.

To prevent the sliding jaw 3 sliding from the shank 2' of Fig. 3, I have provided a 95 pin or screw 21 which may be removed when it is desired to remove the inner jaw, but which otherwise prevents its removal.

In the type of wrench shown in Figs. 1 and 2 the sharp edges formed by the 100 threaded back edge of the wrench would be objectionable, or painful to the hand of the operator. In consequence, it is desirable that this edge be covered. To secure this result I employ a sleeve 6 which may be 105 formed by a piece of sheet metal bent to inclose the handle bar, and having its edges secured together. In the construction indicated the plate is spaced apart at the back edge by means of a filler bar 60. This protecting sleeve is secured in position upon the handle by means of a locking bolt 61

which engages with the teeth of the thread in the back edge of the handle and with the corresponding threads formed in a bore provided at the outer end of the filler bar 60.

- 5 While purely for holding purposes an ordinary bolt or screw may be used for this purpose I prefer to use a bolt which extends the whole length of the sleeve 6 and which has a flat surface 61 at one side, similar to 10 the bolt 4. In this way the sleeve may be quickly freed and adjusted or removed. By sliding it part way out and locking it, the sleeve may serve as a handle extension. I also prefer that the sleeve 6 should at all 15 times extend enough beyond the end of the handle to inclose the bolt operating arm 63. In this case the sleeve wall should have a notch 62 therein to permit swinging this arm outward. This arm is thus protected 20 against injury or accidental turning.

A wrench of the above construction is one which may be cheaply made. It is rapid in its adjustment and also powerful in action.

What I claim as my invention is:

- 25 1. A wrench having a shank provided at one end with a laterally extending jaw, a sleeve slidable upon the shank and having a complementary jaw extending therefrom, the part of the sleeve at the side opposite to 30 the jaw being spaced away from the shank and having a rounded edge, the opening in this edge of the sleeve and the adjacent edge of the shank being threaded, and a threaded locking bolt lying within said sleeve and 35 engaging the threads on said sleeve and on said shank, said bolt having a flat side and one end extending without the sleeve, said outer end being provided with an operating handle.
- 40 2. A wrench having a shank bar provided with a jaw at one end and its back edge provided with rack teeth, a complementary jaw formed by bending a plate about the shank and securing its ends, the back edge 45 of the sleeve thus formed being threaded to match the teeth on the shank and a threaded bolt extending within said sleeve and engaging with the threads of both sleeve and shank and having one flattened side adapted 50 when turned in proper position, to free the shank and permit sliding of the sleeve upon the shank.
- 55 3. A wrench having a fixed jaw and a

shank at right angles thereto, the back 55 edge of said shank being toothed to form a rack, a sleeve surrounding said shank and having complementary jaw members at the front side of the said shank, said sleeve at its back edge being interiorly threaded to 60 match the teeth of the rack and spaced to secure engagement of the threads in both by a locking bolt and a threaded locking bolt having one side cut away to clear the teeth on the shank when properly turned.

65 4. A wrench comprising a handle bar having a jaw extending laterally from one end and having the outer edge toothed to form a rack, a complementary jaw formed by bending a bar about the handle bar and securing its ends, the opening which receives the handle plate being of a size to receive a threaded locking bolt at its back and being threaded to match the teeth upon the handle 70 bar, a threaded locking bar within the back part of the jaw member engaging the threads thereof and of the handle bar and having one side cut away to clear the threads, and a handle sleeve removably secured to the outer end of the handle.

75 5. A wrench having a handle threaded on one edge to form a rack, a sleeve surrounding said arm and providing a bolt-receiving recess at the back of the handle and being 80 interiorly threaded at this edge, a locking bolt entering this recess and extending throughout the length of the sleeve, whereby the sleeve may be secured in different 85 positions upon the handle and serve as a handle extension.

90 6. A wrench having a handle threaded on an edge, a sleeve surrounding said handle and providing a bolt receiving recess outside of said threaded edge of the handle, said 95 recess being similarly threaded, a locking bolt engaging said threads upon handle and sleeve and having a flattened side adapted to clear it from the threads upon the handle when properly turned, said bolt having a laterally extending operating arm upon its outer end and one side of the sleeve being cut away at its outer end to permit said 100 arm turning within the outline of the sleeve 105 when the bolt is in locking position.

Signed at Seattle, King county, Washington, this 21st day of March, 1920.

WILLIAM F. ROTERMUND.
